(57) **CLAIM**

The ornamental design for a combination mounting and fastening bracket for solar structures, substantially as shown and described.

DESCRIPTION

1.1 is a perspective view of the front, top and one side of a combination mounting and fastening bracket for solar structures showing my design;

1.2 is a front view of my design;

1.3 is a rear view of my design;

1.4 is a perspective view of the front, top and one side of my design showing a second mounting and fastening bracket stacked above the first mounting and fastening bracket of **1.1**;

1.5 is a front view of my design showing the second mounting and fastening bracket stacked above the first mounting and fastening bracket of **1.1**; and

(Continued)

1.6 is a perspective view of the rear, top and one side of my design showing the second mounting and fastening bracket stacked above the first mounting and fastening bracket of **1.1**.

The second mounting and fastening bracket of **1.4** to **1.6** shown in low contrast is provided for the purposes of illustrating environmental structure and do not form part of the claimed design.
